Primary Examiner — Wan Laymon

(57) **CLAIM**

The ornamental design for an intra-oral scanning wand, as shown and described.

DESCRIPTION

FIG. 1 is a perspective view of the new design for an intra-oral scanning wand containing an optical sensor for electronically obtaining intra-oral digital images;

FIG. 2 is a right side view thereof, the left side view being a mirror image of the right side view shown;

FIG. 3 is a top view thereof;

FIG. 4 is a bottom view thereof;

FIG. 5 is a front view thereof; and,

FIG. 6 is a rear view thereof.
